Application December 28, 1953, Serial No. 28,257

Term of patent 14 years

(Cl. D1—12)

To all whom it may concern:

Be it known that I, Harry A. Bell, a citizen of the United States, and resident of Oklahoma City, Oklahoma, have invented a new, original, and ornamental Design for a Sign, of which the following is a specification, reference being had to the accompanying drawing, forming a part thereof.

Figure 1 is an elevation of one side of the sign, showing my new design,

Figure 2 is an end elevation of the same,

Figure 3 is an elevation of the opposite side of the device,

Figure 4 is a vertical section taken on line 4—4 of Figure 3, and,

Figure 5 is a plan view of the device.

I claim:

The ornamental design for a sign, as shown.
